(57) **CLAIM**

The ornamental design for a display device capable of receiving an electronic device, as shown and described.

DESCRIPTION

FIG. 1 is a front perspective view of a display device, in accordance with the new design with a base capable of receiving an electronic device, such as a computer host or other peripheral devices, and a support arm for supporting a display panel wherein a cable-packing hole is positioned on the support arm so that the cables of the electronic device can be gathered together by passing through the cable-packing hole.

FIG. 2 is a rear perspective view thereof;

FIG. 3 is a front view thereof;

FIG. 4 is a rear view thereof;

FIG. 5 is a left view thereof;

FIG. 6 is a right view thereof;

FIG. 7 is a top plan view thereof; and,

FIG. 8 is a bottom plan view thereof.
